(57) **CLAIM**

The ornamental design for a solid surface clamp, as shown and described.

DESCRIPTION

FIG. 1 is a front right perspective view of a solid surface clamp showing a clamp device and a bar.

FIG. 2 is a front left perspective view of the solid surface clamp illustrated in FIG. 1.

FIG. 3 is a top view of the solid surface clamp illustrated in FIG. 1.

FIG. 4 is a front view of the solid surface clamp illustrated in FIG. 1.

FIG. 5 is a side view of the solid surface clamp illustrated in FIG. 1.

FIG. 6 is a front right perspective view of the clamp device for the solid surface clamp illustrated in FIG. 1.

FIG. 7 is a side view of the clamp device illustrated in FIG. 6; and,

FIG. 8 is a top view of the clamp device illustrated in FIG. 6.
